UNITED STATES PATENT OFFICE.

GUSTAW MAZURKIEWICZ, OF PETROGRAD, RUSSIA.

CENTRIFUGAL DISTRIBUTING DEVICE.

1,177,201.

Specification of Letters Patent. Patented Mar. 28, 1916.

Application filed July 6, 1915. Serial No. 38,364.

To all whom it may concern:

Be it known that I, GUSTAW MAZURKIEWICZ, engineer, subject of the Emperor of Russia, residing at Petrograd, Russia, have invented certain new and useful Improvements in Centrifugal Distributing Devices, of which the following is a specification.

In sugar refining the masse-cuite is poured after boiling into refining molds of one of 10 the various forms, (*i. e.* cone-shaped, round, square prisms, box-like chamber and so forth), which are usually arranged on a carriage to the extent of 40-50 and more, and then,—all the molds being closed by means 15 of stoppers,—the masse-cuite is cooled in the course of several hours in the filling room, after which, if necessary, it is subjected to ruling and cutting and goes for cleansing to beds or centrifugal apparatus, where it is 20 cleansed by means of liquor.

Lately the process of cleansing with liquor in centrifugal apparatus is commencing to be used with increasing success and in the particular case of using cone-shaped molds 25 the masse-cuite is cleansed just as well as on beds. The liquor is directed into the interior distributing drum of the centrifugal apparatus, into which the loaves of sugar in molds are placed along the circumference 30 in 3 or 4 rows as they arrive from the filling room after cooling, but with the stoppers removed.

According to the present invention, in order to save manual labor and utilize the 35 centrifugal force developed by the centrifugal apparatus, I propose the use of a centrifugal distributing device of a special construction. This device is constructed in order to do away entirely with the hand 40 pouring of the masse-cuite into the molds. Owing to the action of centrifugal force all the masse-cuite entering the distributing device is divided automatically into the required number of equal parts (according to 45 the numbers of molds placed into the centrifugal apparatus) and directed in the molds (preliminarily placed in the centrifugal apparatus empty); the molds having been filled with the masse-cuite the same arrangement can serve to cleanse the latter 50 with liquor without stopping the centrifugal apparatus, thus carrying out both operations,—filling and cleaning,—successively.

In more fully describing my invention 55 reference may be had to the accompanying drawings, which serve to illustrate the in-

vention and form a part of this specification, in which—

Figure 1 is a sectional elevation of a centrifugal apparatus provided with the distributing device constructed in accordance with this invention. Fig. 2 is a view of the centrifugal apparatus having the distributing device inserted therein, the right hand quadrant of the figure being a sectional plan 60 of the whole arrangement and the left hand quadrant a top view of the distributing device, the casing of the centrifugal apparatus being shown in section. Fig. 3 illustrates in detail the distributing device, the left hand half being a side view and the right hand half a sectional elevation of this device. Fig. 4 is a section of one of the upper tubular connections. Fig. 5 is a section of one of the lower tubular connections. Fig. 6 shows in 70 the upper half a section on the line A—B of Fig. 3 and the lower half a plan view of the device. Fig. 7 is a side view of a portion of the middle part of the device, showing three rows of tubular connections. Figs. 80 8 and 9 show sectional elevations of two modified forms of the distributing device, Fig. 8 representing a device for producing or cleansing sugar places and Fig. 9 a device for producing or cleansing loaves of 85 smaller size. Fig. 10 is a section on line C—D of Fig. 8 and Fig. 11 is a plan view of the lower part of the device shown in Fig. 9, partly in section on line E—F.

Referring to the drawings, Figs. 1 and 90 2 show a general view of my distributing device placed in the centrifugal apparatus when working. From the vacuum apparatus or cooler the masse-cuite enters the measuring receptacle 1, from which the measured 95 quantity of masse-cuite flows along the pipe 2, into the centrifugal distributing device 4, filling all the empty molds 3, equally with the masse-cuite. In the drawing 30 molds are taken as an example forming three horizontal rows.

Figs. 3 to 7 illustrate the distributing device in detail. This device 4 consists of a bronze casting (of annular box appearance). The masse-cuite, on flowing out the pipe 2, 105 falls on to turbine-like blades 6, on the top of the inner part of the device which break up the mass and impart initial speed of rotation to it, distributing it equally along the annular shaped inclined surface 7. From 110 this moment until the end of the work, the masse-cuite is under the action of centrifu-

gal force. The cooling of the masse-cuite takes place at the same time as air from the outside is sucked in together with the masse-cuite, delivered through from the pipe 2. 5 penetrating through the annular interstice 2' around the pipe 2. into the rotating distributing device. The flow of air is regulated by reducing or increasing the width of the annular interstice 2'. in a suitable manner. The masse-cuite is thrown against the 10 annular surface 7. and is conducted to an annular chamber 8, where it encounters 30 winged turbine-shaped partitions 9 (according to the number of loaves in this case), 15 dividing the masse-cuite entering therein into equal parts and directing it to 30 openings provided with distributing tubular connections 10, leading the masse-cuite to each 20 separate mold owing to their arrangement in the centrifugal apparatus exactly opposite each mold. The length and section of the 25 tubular connections 10, 10, as well as the number of same and of the partitions 9, 9, the angle of inclination of the surface 7. and 30 all the dimensions and construction in general have to be selected in accordance with the requirements in each case. Thus, Figs. 3-7 represent a device adapted to fill three horizontal rows of molds of normal size, 35 each row containing for instance, ten molds.

Figs. 9 and 11 show an example of a device adapted to be used in the production of sugar plates, the annular chamber 8. being divided in a great number of distributing channels 35 by means of a plurality of partitions 9.

Figs. 9 and 11 show an example of a device adapted to be used in the production of loaves of small size, the molds being disposed in five rows.

40 The centrifugal distributing device is to be used in the following manner: The device 4. is lowered as a whole into the centrifugal apparatus (Fig. 1), which is loaded with empty molds and fastened in it with the aid 45 of latches 11. or the like, the outlets of the tubular connections 10. being disposed opposite the molds. Then the centrifugal apparatus is started. When running at full speed the measured quantity of masse-cuite required to fill the molds is let in, which, in 50 passing along the apparatus, is subjected to cooling, by the current of air entering the centrifugal apparatus with it, and fills the molds and the molasses commences at once 55 to be ejected by centrifugal force from the nose opening of each mold which does not bear any stopper. The masse-cuite owing to the action of centrifugal force is pressed into a firm mass, the molasses is withdrawn by 60 the action of the same force and the air pressing upon same tends to harden the masse-cuite, cooling all of it. When the masse-cuite becomes sufficiently hard and the 65 molasses is withdrawn, a spray of liquor coming from the receptacle 1' through the pipe

2^a is let into the device for cleansing the sugar as in ordinary work.

My device may be used also after the completion of the work of filling and cleansing for the passage of a current of warm dry air 70 with the object of effecting a drying of the sugar in the centrifugal apparatus to the desired limit.

The work with my device does not interfere in any way with previous processes 75 already known.

My device offers the following advantages:

1. The filling of the molds with a minimum expenditure of manual labor. 2. A more rapid distribution of the masse-cuite in the 80 molds and a considerably greater firmness. 3. Accelerated cooling. 4. Doing away altogether with the use of stoppers and with all the operations necessitated thereby, with an enormous saving of time in connection with 85 the operations mentioned (several minutes instead of several hours). 5. Doing away altogether with the ruling of raw loaves. 6. Economy of space in the filling room. 7. Continuous work of the successive processes 90 of refining, filling, cleansing and drying, if desired. 8. An undoubtedly enormous reduction of the inversion of sugar as compared with work on beds in the filling room.

Having now particularly described and 95 ascertained the nature of my said invention and in what manner the same is to be performed, I declare that what I claim is:

1. A rotating distributing device to be used with centrifugal apparatus in the process 100 of refining sugar, comprising a casting having an annular space, blades on the upper part of the inner wall of the said casting adapted to impart to the masse-cuite or cleansing liquor, as the case may be, an 105 initial speed and throw it against the outer wall of the casting, an inclined outer annular wall on said casting, an annular chamber on said casting in which the masse-cuite or cleansing liquor is conducted from the 110 outer inclined wall, partitions dividing the said annular chamber into a number of channels corresponding to the number of molds and tubular connections, the outlets of which lie opposite the inner ends of the molds in 115 the centrifugal apparatus.

2. In a centrifugal distributing device, the combination with a rotary casing having a plurality of rows of molds supported therein, a distributor mounted in the casing consisting of inner and outer walls, blades located at the apex of the inner wall for distributing the masse-cuite as it enters the distributor, a plurality of tubular connections for conducting the masse-cuite from the distributor to the molds, and a plurality of partitions in the distributor for distributing the masse-cuite to the tubular connections. 120

3. In a centrifugal distributing device, the combination with a rotary casing having a 130

plurality of rows of molds supported there-
in, a distributer removably mounted in the
casing consisting of inner and outer walls,
said walls having a space formed therebe-
tween, blades located at the apex of the
inner wall for distributing the masse-cuite
in the space between the walls as it enters
the distributer, and means for conducting
the masse-cuite from the distributer to the
molds, said rotary casing having openings
therein for forming discharge outlets for the
molds, so that the molasses may be ejected
from the molds by centrifugal force.

4. In a centrifugal distributing device,
comprising a rotary distributer having inner
and outer walls, blades on the inner wall
for distributing the masse-cuite as it enters
the distributer, and a plurality of parti-
tions connected to the inner faces of the
inner and outer walls for forming a num-
ber of distributing channels and dividing
the masse-cuite into equal portions in dis-
charging the masse-cuite from the distrib-
uter.

25 5. In a centrifugal distributing device,
comprising a rotary distributer having an
outer wall and an inner cone-shaped wall,
said walls being provided with an annular
space therebetween, blades located at the

apex of the inner wall for breaking up and 30
distributing the masse-cuite in the annular
space as it enters the distributer, said dis-
tributer being provided with a plurality of
outlet openings, and a plurality of parti-
tions connected to the inner surfaces of the 35
outer and inner walls of the distributer for
dividing the masse-cuite into equal portions
and discharging each portion of the mas-
se-cuite through an outlet.

6. In a centrifugal distributing device, the 40
combination of a rotary distributer having
an outer and inner wall, said walls being
provided with an annular space therebe-
tween, blades located on the inner wall for
distributing the masse-cuite into the annu- 45
lar space as it enters the distributer, said
distributer being provided with a plurality
of rows of outlet openings arranged at va-
rious angles, and rows of molds arranged
adjacent to the distributer so that each 50
mold receives the discharge from an inde-
pendent outlet opening.

In testimony whereof I affix my signature
in presence of two witnesses.

GUSTAW MAZURKIEWICZ.
